CLASP FOR JEWELRY CHAINS

Albert C. Nielsen, Chicago, Ill.

Application July 19, 1949, Serial No. 105,481

3 Claims. (Cl. 24—241)

1

My invention relates to clasps for chains which carry watches, bracelets, necklaces, and other jewelry items or novelties, and one object is to provide a clasp which is of ample strength to overcome all pulling strains on the chain.

A further object is to design the clasp with a positive retaining factor, and to secure the latter in a spring receptacle capable of being opened when desired.

Another object is to design the novel clasp along lines of sturdiness and simplicity.

With the above objects in view, and any others which may suggest themselves from the description to follow, a better understanding of the invention may be had by reference to the accompanying drawings, in which—

Fig. 1 is a top plan view of a watch bracelet incorporating the novel clasp in the locked position;

Fig. 2 is an enlarged duplication of the clasp in Fig. 1;

Fig. 3 is a section on the line 3—3 of Fig. 2;

Figs. 4 and 5 are sections on the lines 4—4 and 5—5 of Fig. 3; and

Fig. 6 is a view similar to Fig. 3, showing the clasp open.

In accordance with the foregoing, Fig. 1 shows the top of the clasp; and it is understood that the bottom thereof lies against the wrist or other body portion to which the chain of the jewelry article is applied. The illustration in Fig. 1 is that of a watch 10, the clasp being indicated at 11. The clasp 11 is extended from one end with ears 12 which make a conventional connection with one of the chain links 13. The clasp is designed to make a connection at its opposite end with a lug 14 of the watch 10 or other article carried by the chain, such lug being perforated crosswise, as is the common practice. The illustration in Fig. 1 shows the clasp in locked engagement with the lug 14.

Turning to Figs. 2 and 3, it is seen that the clasp mainly involves a casing 11, formed with pendent side flanges 20. At one end, these are perforated for the hinged suspension of a bottom lid 22, such lid having an upturned bend 23 at its free end and a lug 24 extended from such free end at the center. Lid 22 is hinged as at 22a to flanges 20.

The flanges 20 of the casing 11 converge somewhat in a downward direction; and one of the flanges is cut in the middle with a section which is rolled inwardly to form a bearing 25 for the shank 26 of a hook-like latch 27, the bill of such latch being numbered 28 and parallel to the

shank 26. The inner end of shank 26 is bent out at 29 to lock the latch from sliding out of the bearing 25; and the latch is in this manner rendered pivotable in relation to the casing 11.

When the lid 22 is open and the latch 27 is swung down, as shown in Fig. 6 and indicated by finely-dotted lines in Fig. 4, the free end of its bill 28 is open to receive the lug 14 of the watch 10, or of any other novelty designed to be engaged by the clasp. When the lug 14 has been slung on the latch bill 28 and slid onto the bight portion of said latch 27, the latter is swung up toward the casing 11. Now, the spacing of the bill 28 from the hinged shank 26 of the latch is such that the bill will meet some resistance from the proximate casing flange 20 when entering the casing 11, said bill 28 yielding slightly before it seats within the corresponding flange 20. This is possible because the latch 27 is made of spring wire.

After the latch 27 has been seated in the casing as just mentioned and indicated in Figs. 2 to 4, the lid 22 is swung to close on the casing. For this purpose, the end flange 23 of the lid is made with concavities 30 in its side edges; and these edges are spaced to crowd the shank and bill of the latch 27 apart as the lid closes fully on the casing to the extent shown in Figs. 3 and 4. This action momentarily causes the latch to expand to the extent of slightly forcing the side flanges 20 of the casing apart. However, when the lid seats fully in the casing, the shank 26 and bill 28 of the latch trip into or seat in the concavities 30 of the flange 23, allowing the flanges 20 of the casing to assume their normal or convergent positions. The latch is now locked within the casing flanges; and the lid 22 is locked in the closed position by the seating of the latch shank and bill in the concavities 30 of the lid bend 23.

The clasp may thus be considered as completely locked; and it is understood, in the first place, that the longitudinal pull of the chain or other article in which the clasp is interposed, cannot open the clasp because of the positive and closed tie formed by the latch 27. Further, the latch cannot open of itself because of the locked condition previously described, and also because there would be no tendency to pull the lid 22 open as long as it lies against the wrist or other body portion carrying the jewelry article. However, in case the clasp is desired to be opened, the finger-nail may be applied above the lug 24 with downward pressure, in which event the tension of the latch and casing flanges 20 will be overcome, allowing the lid to open.

It is now apparent that the novel latch

constitutes a coupling for articles of the character described which in normal use is a positive lock against the separation of the parts connected, the action of the lock being fortified against accidental failure by the protective position of the wrist or other body portion against which the lid of the clasp lies. Yet, when it is desired to open the clasp, it is merely placed where its lid can secure a clearance on the application of the fingernail pressure, the clasp readily opening in such event to permit the uncoupling or application of the parts connected. Further, it is evident that the novel clasp is made up of only three parts, which may be made by suitable methods to serve efficiently and be durable over a long period of use. Finally, the simplicity of the clasp makes its manufacture economical and renders it unlikely to get out of order.

While I have described the invention along specific lines, various minor changes or refinements may be made therein without departing from its principle, and I reserve the right to employ all such changes and refinements as may come within the scope and spirit of the appended claims.

I claim:

1. A clasp for coupling jewelry elements comprising a channel form body member providing side flanges and having a coupling means at one end, a hook-shaped latch providing shank and bill portions and having a bight portion projecting as a releasable coupling element from the opposite end of said body, hinge means connecting said shank portion to said body inwardly of and substantially parallel with one of said flanges to dispose said bill inwardly of and adjacent the opposite flange, the latter flange having a resilient outwardly actuatable portion disposed in the path of said bill portion and confiningly overlying a portion of said bill portion when the latter has been swung in to a position adjacent said body, a body-carried means shiftably secured thereto and movable to sustainingly engage the side portion of said bill which is remote from said second-mentioned flange to urge the opposite side of said bill against the latter, said latch being of spring material, and said body-carried means comprising a shiftable lid positioned to close upon the flanged side of said body, said lid including a bend toward the body, said bend entering between said flanges to be effective with its sides to crowd the bill and shank apart on the closing movement of the lid and put the bill in tensioning engagement with the adjacent flange.

2. A clasp for coupling jewelry elements comprising a channel form body member providing side flanges and having a coupling means at one end, a hook-shaped latch providing shank and bill portions and having a bight portion projecting as a releasable coupling element from the opposite end of said body, hinge means connecting said shank portion to said body inwardly of and substantially parallel with one of said flanges to dispose said bill inwardly of and adjacent the

opposite flange, the latter flange having a resilient outwardly actuatable portion disposed in the path of said bill portion and confiningly overlying a portion of said bill portion when the latter has been swung in to a position adjacent said body, a body-carried means shiftably secured thereto and movable to sustainingly engage the side portion of said bill which is remote from said second-mentioned flange to urge the opposite side of said bill against the latter, said latch being of spring material, and said body-carried means comprising a shiftable lid positioned to close upon the flanged side of said body, said lid including a bend toward said body, said bend entering between said flanges to be effective with its sides to crowd the bill and shank apart upon the closing movement of the lid and put the bill in momentary tensioning engagement with the adjacent flange, and said bend sides being formed with recesses behind their leading portions to trip the shank and bill as the lid closes and cause the latter to become locked to the encased latch.

3. A clasp for coupling jewelry elements comprising a channel form body member providing side flanges and having a coupling means at one end, a hook-shaped latch providing shank and bill portions and having a bight portion projecting as a releasable coupling element from the opposite end of said body, hinge means connecting said shank portion to said body inwardly of and substantially parallel with one of said flanges to dispose said bill inwardly of and adjacent the opposite flange, the latter flange having a resilient outwardly actuatable portion disposed in the path of said bill portion and confiningly overlying a portion of said bill portion when the latter has been swung in to a position adjacent said body, a body-carried means shiftably secured thereto and movable to sustainingly engage the side portion of said bill which is remote from said second-mentioned flange to urge the opposite side of said bill against the latter, said latch being of spring material, and said body-carried means comprising a lid hinged to the body at its first mentioned end to close toward the flanged side of said body and toward its other end, said lid having an inward bend entering between said flanges, the sides of said inward bend being effective to crowd the bill and shank apart on the closing movement of the lid and put the bill in momentary tensioning engagement with the adjacent flange, and said sides being formed with recesses behind their leading portions into which the shank and bill trip as the lid closes and cause the latter to become locked to the encased latch.
